UNITED STATES PATENT OFFICE.

DAVID HONOROF, OF GARY, INDIANA.

REMOVER.

1,071,421.

Specification of Letters Patent. Patented Aug. 26, 1913.

Application filed January 20, 1912. Serial No. 672,423.

To all whom it may concern:

Be it known that I, DAVID HONOROF, a citizen of the United States, residing at Gary, in the county of Lake and State of Indiana, have invented new and useful Improvements in Removers, of which the following is a specification.

The general object of the invention is to facilitate the operation of lifting or drawing a liquid from a relatively deep and narrow receptacle and to this end the invention consists in a barrel or container for the liquid to be drawn or lifted and having one end portion adapted for insertion into the receptacle from which the liquid is to be removed, and means for creating a vacuum in the barrel whereby the liquid from the receptacle will be forced upwardly into the barrel under the action of atmospheric pressure.

Other objects will appear and be better understood from the following description taken in connection with the accompanying drawings in which:—

Figure 1 is a side elevation partly in section of one embodiment of the invention. Fig. 2 is an enlarged detail section of the valve for controlling the passage to one end of the barrel also showing the bulb or aspirator connected to the valve. Fig. 3 is a detail cross section of the valve. Fig. 4 is a detail cross section on the line 4—4, on Fig. 1.

The barrel or receptacle 5 may be of any desired volume and may also be formed of any suitable material such as metal. This barrel or receptacle has at one end a spout or nozzle A whose diameter is relatively small as contrasted with that of the barrel or receptacle. The spout or nozzle A is extensible and consists of an inner tube 6 over which slides the outer tube 7 having at one end a suitable gasket 8 which frictionally contacts the tube 6 whereby to prevent the escape of air or liquid, the opposite end of the outer tube 7 being provided with a screen of suitable construction such as a perforated nipple 9 which connects to the outer end of the tube 7.

By the provision of the extensible spout or nozzle A the device is particularly adapted for use in connection with removing liquid from such receptacles as bottles and in this connection it will be observed that the device is peculiarly adapted for separating the lighter of two liquids of different specific gravities such as the cream from the

milk in the ordinary milk bottle, since it will be manifest that, if the length of the spout or nozzle when fully extended corresponds to the length of the bottle, the said spout may be adjusted so as to extend into the cream only, regardless of the quantity of liquid in the bottle.

The liquid is drawn or lifted through the spout or nozzle and into the container by the suction produced by a rubber bulb 10 which has a tube 11 which suitably connects to the open end 12 of a tubular two-way valve 13 adapted for turning in a reduced tubular extension 14 on the upper end of the barrel or container 5.

By turning the valve 13 so that the ports or passages 15 and 17 will communicate with the open end of the extension 14, communication will be cut off between bulb 10 and interior of the barrel 5. When the valve is so turned the air which is expelled from the bulb by collapsing the same will pass into the atmosphere. By holding the bulb collapsed and turning the valve 13 by means of the hand-hold 16 until the ports 15 and 18 communicate with the barrel 5, the port 17 will be turned away from the open end of the extension 14 so that when the bulb is permitted to expand by releasing the same a vacuum will be created in the stem or nozzle and barrel or container 5 whereby, if the said nozzle be inserted into liquid the same will be forced upwardly through and into the barrel 5 under the action of atmospheric pressure. If less than the desired quantity of liquid passes into the barrel under the first expansion of the bulb, then the quantity so drawn may be added to by first turning the valve until the ports 15 and 17 thereof communicate with the atmosphere. The bulb is then compressed or collapsed after which the valve is turned until the ports 15 and 18 thereof again communicate with the container 5 whereupon liquid will again flow into the container when the bulb is released. With this construction it will be manifest that the quantity of liquid may be increased in the container without the necessity of first expelling through the nozzle the liquid which is in the container and then suddenly releasing the bulb which practice naturally would have to be resorted to if the valve 13 were not present in the structure. Therefore by operating the valve as just described the container may be filled without

removing the nozzle from the liquid and without agitating the latter so as to cause the heavier liquid to mix with the lighter.

Although I have shown and described one embodiment of the invention it is to be understood that I am not to be limited to the same since various changes may be made within the scope of the claims without departing from the spirit of the invention.

Having thus fully described the invention, what I claim as new, is:—

In a remover the combination of a hollow body, a hollow stem leading from one end of the body and communicating therewith, a valve plug operative in the stem and projecting in both directions beyond the same, said plug within the hollow portion of the

stem being formed with angularly related ports communicating with the interior of the plug, the projection of the plug in one direction beyond the stem having a closed terminal and formed to serve as a handle for operating the plug, the projection of the plug in the opposite direction beyond the stem having an open end, and a bulb connected to the open end of said valve plug.

In testimony whereof I affix my signature in presence of two witnesses.

DAVID HONOROF.
